SHEET METAL HOLDER

Ernest F. Wooster, San Diego, Calif.

Application October 30, 1940, Serial No. 363,407

5 Claims. (Cl. 85—5)

My invention relates to a sheet metal holder, more particularly for use in holding two or more sheets of metal together in fixed flat engaged relation with each other while drilling said sheets of metal and forming spaced rivet receiving or like holes therein and the objects of my invention are:

First, to provide a sheet metal holder of this class which is made of a single piece of spring metal and is so arranged that when positioned in aligned adjacent holes of separate sheets of metal, said separate sheets of metal are held securely together and said adjacent holes are maintained in accurately aligned relation with each other;

Second, to provide a sheet metal holder of this class which maintains a relatively forceful tensional engaged relation with opposite outer sides of adjacent flat sheets of metal when inserted and positioned in aligned holes in said adjacent sheet of metal;

Third, to provide a sheet metal holder of this class which is made of a single piece of resilient metal wire and which may accommodate various thicknesses of sheet metal;

Fourth, to provide a sheet metal holder of this class which is easily inserted in aligned holes in adjacent sheet metal plates;

Fifth, to provide a sheet metal holder of this class which is very simple and easy to operate and which may be very quickly inserted in holes in sheets of metal with a minimum of time and effort expended;

Sixth, to provide a sheet metal holder of this class which is self-contained, compact and very accurate in operation;

Seventh, to provide a novel sheet metal holder of this class;

Eighth, to provide a sheet metal holder of this class which maintains a tenacious grip within holes in adjacent sheets of metal so that said sheet metal holder is not easily moved from its position within said holes and therefore it must be finally manually removed from said holes as desired; and

Ninth, to provide a sheet metal holder of this class which is very simple and economical of construction, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being

had to the accompanying drawing and to the characters of reference thereon which form a part of this application in which:

Figure 1 is a side elevational view of my sheet metal holder shown positioned in connection with two sheets of metal and inserted in aligned holes therein, said sheets of metal being shown in section and a varying position of portions of my sheet metal holder being shown by dash lines; Fig. 2 is a side elevational view of my sheet metal holder showing the opposite side thereof from that as shown in Fig. 1 and showing two sheets of metal in connection with my sheet metal holder, said sheets of metal being shown in section; Fig. 3 is an enlarged fragmentary sectional view taken from the line 3—3 of Fig. 2; Fig. 4 is an elevational view taken from the line 4—4 of Fig. 1; Fig. 5 is a fragmentary sectional view taken from the line 5—5 of Fig. 3 showing portions in elevation to facilitate the illustration; Fig. 6 is a fragmentary side elevational view showing a modified form of my sheet metal holder in connection with two sheets of metal, which sheets of metal are shown in section, and also showing by dash lines a varying position of a portion thereof; Fig. 7 is a fragmentary sectional view taken from the line 7—7 of Fig. 6 and Fig. 8 is a longitudinal sectional view taken from the line 8—8 of Fig. 7.

Similar characters of reference refer to similar parts and portions throughout the several views of the drawing.

In the construction of my sheet metal holder, I have employed a resilient piece of wire material and have formed in the middle portion thereof a coil spring portion 1. Diverging outwardly from this coil spring portion 1 are arm portions 2 and 3, as shown best in Figs. 1 and 2 of the drawing. The extended end portion of the arm portion 3 is provided with a substantially U-shaped portion 3a, as shown best in Fig. 3 of the drawing. Extending upwardly from the U-shaped portion 3a and backwardly therefrom is a substantially semi-circular curved portion 3b integral with which is a semi-circular in cross section portion 3c, as shown best in Figs. 1, 2 and 3 of the drawing. This semi-circular in cross section portion 3c is provided with an extending end portion 3d which extends a short distance outwardly from the U-shaped portion 3a at the opposite side thereof from the substantially semi-circular curved portion 3b.

It will be noted that the semi-circular in cross section portion 3c extends through the U-shaped portion 3a in conforming relation with the semi-

circular in cross section portion $2a$ of the arm portion 2 , as shown best in Fig. 3 of the drawing. These semi-circular cross section portions $2a$ and $3c$ are positioned together so that they form a substantially annular in cross section structural relation, as shown best in Fig. 3 of the drawing.

The extended end portion $2b$ of the semi-circular in cross section portion $2a$ is provided with a detent stop portion $2c$, which stop portion $2c$ is arranged to engage the side surface of sheet metal surrounding the hole A therein, as shown best in Fig. 5 of the drawing.

The operation of my sheet metal holder is substantially as follows:

When it is desired to hold two sheets of metal in certain aligned relation for drilling the two sheets of metal while positioned in flat contact relation with each other, the drilled holes will coincide and align with each other in relation with both sheets of metal. The sheets of metal are provided with holes A therein, as shown best in Fig. 5 of the drawing. The arm portion 2 of my sheet metal holder is pressed into the dash line position B so that the end portion $2b$ of said arm portion 2 extends outwardly some distance from the solid line position, as indicated by dash lines in Fig. 1 of the drawing. This end portion $2b$ is then inserted through the holes A in the separate sheets of metal and the stop detent portion $2c$ is positioned beyond the further side of the sheets of metal. The end portion $3d$ is then inserted in the holes A in conforming relation with the holes A in the metal and the arm portion 2 is then released and permitted to be forced into the solid line position by means of the resilient character of the coil spring portion 4 forcing the detent stop portion $2c$ against the opposing side of these sheets of metal from the U-shaped portion $3a$ of the arm portion 3 , as shown best in Figs. 1 and 5 of the drawing. It will be here noted that when my sheet metal holder is positioned in connection with sheets of metal in the inserted relation, as shown best in Fig. 5 of the drawing, the semi-circular in cross section portions $3c$ and $2a$ in their relation as shown in Fig. 3 of the drawing conform to the annular shape internally of the holes A in the sheets of metal, which holes A are formed in the conventional manner by means of a conventional drill.

When it is desired to drill holes in adjacent sheets of metal, holes are drilled in both sheets of metal in spaced relation. Then one of my sheet metal holders is positioned in each of the holes and the two sheets of metal are thereby held in rigid aligned relation so that the holes may be accurately drilled, whereby the holes in separate sheets of metal are maintained in accurate aligned relation with each other for drilling and riveting.

The modification, as shown in Figs. 6, 7 and 8 of the drawing performs the same function in substantially the same manner as the structure described in connection with Figs. 1 to 5 inclusive of the drawing. The modified form, as shown in Fig. 6 of the drawing is provided with a coil spring portion 4 , which spring portion 4 is of the helical type having the end portion $4a$ thereof curved inwardly toward the central portion of the coil spring portion 4 . In connection with this inwardly curved portion $4a$ is a semi-circular in cross section portion $4b$ extending longitudinally through the central portion of the coil spring portion 4 , as shown best in Figs. 6 and 7 of the drawing. In connection with the opposite end of the coil spring portion 4 is an in-

wardly curved portion $4c$ integral with which is a substantially U-shaped portion $4d$ through which the semi-circular in cross section portion $4b$ extends. Integral with this semi-circular in cross section portion $4b$ is an extending end portion $4e$. This end portion $4e$ is provided with a detent stop portion $4f$ which is substantially the same shape and construction as the end portion $2b$, as shown in Fig. 5 of the drawing and its respective detent stop portion $2c$. Integral with the U-shaped portion $4d$ is a substantially semi-circular portion $4g$ which is provided with a semi-circular in cross section portion $4h$ extending in parallel relation with the semi-circular in cross section portion $4b$. This semi-circular in cross section portion $4h$ corresponds in shape and operation to the semi-circular in cross section portion $3c$ of the structure as shown in Fig. 5 of the drawing.

20 It will be here noted that the modified form of my sheet metal holder, as shown in Figs. 6 to 8 inclusive corresponds in operation and functions to the structure as shown in Figs. 1 to 5 inclusive, the coil spring member 4 of the modification being arranged to correspond in function to the coil spring portion 1 of the structure disclosed in Figs. 1 to 5 inclusive. The coil spring portion 1 , as shown in Fig. 1 of the drawing, and the coil spring portion 4 , as shown in the modified form in Fig. 6 of the drawing are arranged to impart tensional engaged relation of the detent portions $2c$ and $4f$ respectively at the opposite side of the sheets of metal from the U-shaped portion $3a$ and $4d$ respectively of the structure shown in Figs. 1 to 5 inclusive and the modified structure shown in Figs. 6 to 8 inclusive, respectively.

Though I have shown and described a particular construction, combination and arrangement of parts and portions and a certain modification, I do not wish to be limited to this particular construction, combination and arrangement, nor to the modification, but desire to include in the scope of my invention the construction, combination and arrangement substantially as set forth in the appended claims.

Having thus described my invention, what I claim as new and desire to secure by Letters Patent is:

50 1. In a sheet metal holder of the class described, the combination of a single piece of spring metal provided with a resilient spring portion intermediate its opposite end portions, the opposite end portions of said single piece of spring metal each being semi-circular in cross section and both arranged together in parallel annular in cross section form, one of said opposite end portions being longitudinally shiftable and the other end portion being stationary, said shiftable end portion provided with a detent stop portion extending outwardly from the semi-circular side portion thereof, said resilient spring portion being of coil form, and a U-shaped portion at one end of said resilient spring portion arranged to support and guide said semi-circular in cross section end portions.

55 2. In a sheet metal holder of the class described, the combination of a single piece of spring metal provided with a resilient spring portion intermediate its opposite end portions, the opposite end portions of said single piece of spring metal each being semi-circular in cross section and both arranged together in parallel annular in cross section form, one of said opposite end portions being longitudinally shiftable

and the other end portion being stationary, said shiftable end portion provided with a detent stop portion extending outwardly from the semi-circular side portion thereof, said resilient spring portion being of coil form, a U-shaped portion at one end of said resilient spring portion arranged to support and guide said semi-circular in cross section end portions, and an extending curved portion immediately connected with said U-shaped portion with which said stationary 10 semi-circular in cross section end portion is immediately integral.

3. In a sheet metal holder of the class described, the combination of a single resilient piece of metal wire having a spring portion intermediate its opposite end portions, said opposite end portions arranged in parallel relation to each other, one of said opposite end portions shiftable relatively with the other end portion, said shiftable end portion provided with a detent stop portion extending outwardly from the side thereof, a U-shaped portion at one end of said spring portion arranged to support and guide said opposite end portions, both of said opposite end portions extending some distance past said U-shaped portion.

4. In a sheet metal holder of the class described, the combination of a single resilient piece of metal wire having a spring portion intermediate its opposite end portions, said opposite end portions arranged in parallel relation to each other, one of said opposite end portions

shiftable relatively with the other end portion, said shiftable end portion provided with a detent stop portion extending outwardly from the side thereof, a U-shaped portion at one end of said spring portion arranged to support and guide said opposite end portions, both of said opposite end portions extending some distance past said U-shaped portion, and an extending curved portion immediately connected with said U-shaped portion with which said other end portion is immediately integral.

5. In a sheet metal holder of the class described, the combination of a single piece of spring metal provided with a resilient spring portion intermediate its opposite end portions, the opposite end portions of said single piece of spring metal each being semi-circular in cross section and both arranged together in parallel annular in cross section form, one of said opposite end portions being longitudinally shiftable and the other end portion being stationary, said shiftable end portion provided with a detent stop portion extending outwardly from the semi-circular side portion thereof, said resilient spring portion of coil form, and a U-shaped portion at one end of said resilient spring portion arranged to support and guide said semi-circular in cross section end portion, both of said opposite end portions extending some distance past said U-shaped portion.

ERNEST F. WOOSTER.
